(57) **CLAIM**

The ornamental design for an air freshener container, as shown and described.

DESCRIPTION

FIG. 1 is a right front perspective view of the an air freshener container;

FIG. 2 is a right bottom perspective view thereof;

FIG. 3 is a front elevation view thereof;

FIG. 4 is a right side elevation view thereof;

FIG. 5 is a rear elevation view thereof;

FIG. 6 is a left side elevation view thereof;

FIG. 7 is a top plan view thereof;

FIG. 8 is a bottom plan view thereof;

FIG. 9 is a right front perspective view of the container with the lid shown removed to illustrate details not visible in other views;

FIG. 10 is a right bottom perspective view thereof;

FIG. 11 is a front elevation view thereof;

FIG. 12 is a right side elevation view thereof;

FIG. 13 is a rear elevation view thereof;

FIG. 14 is a left side elevation view thereof;

FIG. 15 is a top plan view thereof; and,

FIG. 16 is a bottom plan view thereof.

The broken lines are shown for the purpose of illustrating unclaimed portions of the air freshener container and form no part of the claimed design.

No claim boundary lines are shown in the disclosure; the long and short regularly spaced lines are shown for the purpose of showing curvature and contour only.

1 Claim, 16 Drawing Sheets
